UNITED STATES PATENT OFFICE.

HENRY G. MCLEMORE, OF COLUMBUS, GEORGIA.

CHECK ATTACHMENT FOR LOOMS.

Application filed May 19, 1926. Serial No. 110,218.

This invention relates to a check attachment for loom picker sticks and has for its object to provide, in a manner as hereinafter set forth a new and novel form of check attachment for picker sticks to increase the output of the loom for a predetermined period, as well as to materially decrease the cost of maintenance in connection with the operation of the loom, and furthermore to overcome the use of check straps now generally employed for checking the picker sticks, as such check straps quickly deteriorate or become damaged resulting in increased cost of maintenance and further reducing the output of the looms for predetermined periods.

Further objects of the invention are to provide, in a manner as hereinafter set forth a check attachment for loom picker sticks which is simple in its construction and arrangement, strong, durable, thoroughly efficient in its use, readily installed with respect to the battery right or battery end and the left or lever end of the loom, and comparatively inexpensive to manufacture.

With the foregoing and other objects in view, the invention consists of the novel construction, combination and arrangement of parts as hereinafter more specifically described and illustrated in the accompanying drawings wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is an elevation of a lay of a loom showing the adaptation therewith of a picker stick check attachment in accordance with this invention and further showing the picker sticks.

Figure 2 is a top plan view of the lay showing the adaptation therewith of a check attachment in accordance with this invention.

Figure 3 is a section on line 3—3, Figure 2.

Figure 4 is an inverted plan view of one end of the lay, at that end thereof arranged at the left or lever end of the machine and showing the adaptation therewith of one pair of binder elements forming a part of a check attachment in accordance with this invention.

Figure 5 is an inverted plan view of the end of the lay at the battery end of the loom and showing the adaptation therewith of a pair of binder elements forming a part of a check attachment in accordance with this invention.

Figure 6 is a side elevation of one of the binding means.

Figure 7 is a perspective illustrating a spacing block and a binder element disassembled.

Figure 8 is a perspective view of a binder element and its support and which is employed at the right or battery end of the loom.

Figure 9 is a perspective view of another one of the binder elements.

Referring to the drawings in detail 1 denotes a frame, forming a portion of a loom, 75 and 2, 3 picker sticks. The picker stick 2 is arranged at the right or battery end of the loom and the picker stick 3 at the left or lever end thereof. Supported by the frame 1 is a lay 4 and which has each of its ends bifurcated and the bifurcated ends of the lay 4 at the battery end of the loom is indicated at 5 and the bifurcated end arranged at the lever end of the loom is indicated at 6. The furcation in the end 5 is designated at 7 and that in the end 6 at 8. The picker stick 2 extends up through the furcation 7 and the picker stick 3 extends up through the furcation 8. The shuttle boxes are designated at 9. The picker sticks 2 90 and 3 are pivotally connected as at 10. The bifurcated end 5 of the play 4 provides a pair of arms 11, 12 and the bifurcated end 6 provides a pair of arms 13, 14. The picker sticks 2, 3 are operated in the known manner. 95 The foregoing elements are of known construction with the exception of the manner in which arm 12 is formed and against which is secured the quill chute 14.

The picker stick check attachment for looms, in accordance with this invention, includes a pair of spring controlled binder elements pivotally connected with the end 6 of the lay 4 and a pair of spring controlled binder elements supported below the plate 100 4 at the end 5 thereof and top of the quill chute 14.

The pair of binder elements positioned at the end 6 of the lay 4 are indicated generally by the reference characters 15 and 16 and are oppositely disposed with respect to each other and further are arranged against the

lower face of the lay 4 and normally extend across the furcation 8, see Figure 4. As the binder element 15 is constructed in the same manner as the binder element 16, but one will be described, as the description of one will apply to the other. The binder element 15, as well as the binder element 16 comprises a check portion 17 carried by a shank 18. The check portion 17 is of greater width than the shank 18 and the latter is pivotally connected as at 19 to the arm 13 or 14, that is to say to the lower face thereof and the outer end of the shank 18 merges into the inner end of the check portion 17. The shank 18 is pivotally connected at the longitudinal median of the arm 13 or 14. The outer side of the check portion 17 forms a continuation of the plane of the outer side of the shank 18 and the forward end of the latter on its inner side is rabbeted as at 20. The outer end of the check portion 17 is squared as indicated at 21 and the inner outer corner of said check portion 17 is rounded as at 22. The inner side of the check portion 17 extends upon two different inclinations as indicated at 23, 24 and the inclination is towards the outer side of the check portion 17. The inclined portion 23 formed on the inner side of the check portion 17 is of greater length than the inclined portion 24 and the latter extends at a greater inclination than the inclined portion 23. The end 21, as well as the inner side of the check portion 17 has secured thereto a wear strip 25 of any appropriate material. The wear strip 25 extends from the rabbet 20 and has its outer face flush with the inner side of the shank 18. Secured to the arm 13, by a hold fast device 26 is the inner end of a controlling spring for the binder element 16 and said spring is indicated at 27, and is so formed whereby the inner portion thereof will be arranged above its forward portion. The inner portion of the spring 27 is indicated at 28 and the forward portion at 29. The forward portion 29 is upon a compound curve and bears against the outer side of the check portion 17 of the binder element 16. Secured to the arm 14 by the hold fast device 30 is the inner end of a controlling spring 31 for the binder element 15. The controlling spring 31 is set up in the same manner as the controlling spring 27. The springs 27 and 31 set to normally maintain the binder elements 15 and 16 in the path of the picker stick 3. The binder elements 15 and 16 have their outer ends positioned inwardly with respect to the outer ends of the arms 14 and 13. The controlling springs 27 and 31 further act to maintain the check portion 17 of the binder elements 15 and 16 in abutting engagement. The setting of the inner sides of the binder elements 15 and 16 in the manner as referred to permits the

free entrance of the picker stick 3 between the check portions 17 for the purpose of shifting the binder elements 15 and 16 in opposite directions and against the action of their controlling spring and these latter act 70 to cause the check portions 17 to bind against the picker stick 3 and check the same. When the picker stick 3 moves from between the check portion 17 the springs 27 and 31 cause the binder elements to move towards each other to the extent whereby the check portion 17 thereof will abut. 75

The outer portion of the arm 12 is of less height than the arm 11 but the upper face of the said outer portion of the arm 12 is flush with the upper face of the arm 11. By setting up the outer portion of the arm 12 of less height than the arm 11 a shoulder 32 is provided, see Figure 1, and against which abuts the quill chute 14', and the latter is provided with an extension 33, secured to the arm 12 by the hold fast devices 34. The extension 33 projects laterally from the arm 12 as indicated at 35. The lateral projecting portion 35 of the extension 33 is formed with an opening 36. Mounted on the lateral portion 35 of the extension 33 is the upper dotted arm 37 of a yoke-shaped support 38 which depends from the extension 33. The other arm of the support 38 is indicated at 39 and is of greater length than the arm 37 and extends inwardly an appropriate distance and is spaced from the extension 33, as well as being arranged below the same. The arm 39 provides a support for one of the binder elements positioned at the battery end of the loom.

Secured to the lower face of the arm 11, by the hold fast devices 40 is a spacing block 41 formed with openings 42 for the passage of the hold fast devices 40. The spacing block 41 at its rear end has a reduced extension 43, a shoulder 44 and a beveled outer lower corner 45 which forms a clearance. The other binder element employed at the battery end of the loom is pivotally supported from the spacing block 41.

The binder elements arranged at the battery end of the loom are indicated generally by the reference characters 46, 47 and when arranged in position are oppositely disposed with respect to each other. As each of the binder elements 46, 47 is of the same construction, but one will be described, as the description of one will apply to the other. The binder element 46, as well as the battery element 47 has its inner side inclining away from its outer side from its inner towards its outer end and said inner side is indicated at 48. By this construction the binder element gradually decreases in width from its inner towards its outer end. The outer side 49 of the binder element is squared, as well as its inner end 50 and its outer end 51. The inner outer corner of the binder is rounded as at 130

52. The inner side 48 of the binder is formed with a vertically disposed shoulder 53. Abutting against said shoulder and extending around the corner 52 and to the forward end of the outer side 49 of the binder is a wear strip 54 of appropriate material. The strip 54 is flush with the upper and lower faces of the binder elements and is suitably secured therewith. The binder element 10 centrally of its reduced or inner end is formed with an opening 55.

The binder elements 46 and 47 are spring controlled and that part of each to which the strip 54 is connected and indicated at 56 is termed a check portion. The controlling springs for the binder elements 46 and 47 normally maintain them in abutting position and across the furcation 7. See Figure 2. The controlling spring for the binder element 20 46 is indicated at 57 and the controlling spring for the binder element 47 is indicated at 58. The inner end of the spring 57 is secured to the arm 11 by the hold fast device 59 and said controlling spring includes an upper inner portion 60 and a lower outer portion 61 which bears against the outer side of the binder element 46 at the outer part thereof. The spring 57 is curved so as to provide the inner and outer portions 60, 61 respectively. The controlling spring 58 for the binder element 47 has its inner end secured to the vertical arm of the member 38 by the hold fast device 62. The spring 58 is curved and extends inwardly towards the binder element 47 and the outer end of the spring 58 bears against the outer side of the element 47 at the outer end thereof.

The binder element 46 is arranged below the spacing block 41 and has its inner end 40 pivotally connected therewith by a pivot bolt 63 which extends through the opening 55 in the binder element 46 and engages in the spacing block 41. The binder element 47 is pivotally connected to the arm 35 by a pivot bolt 64 which extends through the opening 55 in said binder element 47 and also extends through an opening 65 formed in the arm 39. A securing nut 66 is carried on the lower end of the bolt 64 and a washer 67 is interposed 50 between the head of the bolt and the binder element 47. A washer 68 is interposed between the block 41 and the binder elements 46. A hold fast device 69 extends through the opening 36 and through the slot of the arm 37 whereby the support 38 is connected to the lateral portion of the extension 33. The binder elements 46 and 47 oppose each other and the arrangement of the spacing block 41 and the height of the support 38 provides 60 for such arrangement, see Figure 3. The setting up of the binder elements 46 and 47 in the manner as shown that is to say providing them with the inclined inner sides permits of the picker stick 2 easily entering between 65 said binder elements and the controlling

springs for these latter will act to check the picker stick 2. When the picker stick 2 moves away from the binder elements, the controlling spring for these latter shift them into abutting engagement at the check portion 70 56. The binders at the lever end of the loom align with the binders at the battery end of the loom. Each pair of binders close when the picker stick is jerked forward and checks the picker stick about two inches 75 from the end of the lay when the picker stick drops back.

The lay 4, as is well known, is not constructed alike at both ends. At the left or lever end of the loom the lay is about three 80 inches wide with a slot in it for the picker stick to work in and is level on its lower face which makes it possible for binders to be fastened to the bottom of the lay, one on the front and one on the rear side positioning 85 the binders on a level with each other and with one opposing the other. That end of the lay at the right or battery end of the loom is about one and one half inches wide, as the front part of such end of the lay has 90 been cutaway to allow the quill chute to be placed in position, whereby provision is only had to fasten the back or rear binder in position to the lower face of the lay. The front binder has to be fastened to the quill chute, there being no front part of the lay to fasten the front binder to. The quill chute is arranged about one and one quarter of an inch below the lower face of the lay, therefore it becomes necessary to use a spacing block on 95 the lower face of the lay at the back, to bring it down to a level with the quill chute, then by fastening the block to the bottom of the lay at the back thereof, it positions the back binder on a level with the front binder which 100 operates on the support fastened to the quill chute, and by this arrangement the front and back binders are in alignment and 105 oppose each other.

It is thought the many advantages of a 110 picker stick check attachment for looms in accordance with this invention, can be readily understood, and although the preferred embodiment of the invention is as illustrated and described yet it is to be understood that 115 changes in the details of construction can be had which will fall within the scope of the invention as claimed.

What I claim is:

1. A check attachment for loom picker sticks comprising two pairs of spring controlled binder elements, means for pivotally connecting one pair of binder elements directly to the lower face of a lay at the left or lever end of the loom, the controlling spring for the binder elements at the lever end of the loom connected to the sides of the lay and bearing against the outer side of such binder elements, a spacing block 120 secured directly to the lower face of the lay 125 130

at the right or battery end of the loom, a support adapted to be secured to a quill chute at the battery end of the loom, a binder element having its inner end pivotally supported from and arranged below said block, a binder element pivotally connected to said support and opposing the binder element arranged below said block, and a pair of controlling springs for said last mentioned binder elements, one of said controlling springs adapted to be connected to the lay and bear against the binder element pivotally supported from said block, and the other of said controlling spring carried by the support and bearing against the binder element pivoted therewith.

2. A check attachment for loom picker sticks comprising a pair of oppositely disposed spring controlled binder elements, means for pivotally connecting the inner ends of said elements to the lower face of a lay at the lever end of the loom, a spacer block adapted to be secured to the lower face of the lay at the battery end of the loom, a support adapted to be connected to a quill chute at the battery end of the loom and further arranged below the lay, and a pair of spring controlled binder elements, one of the elements of said last mentioned pair having its inner end pivotally connected to said block and the other element having its inner end pivotally connected to said support, said last mentioned pair of binder elements being oppositely disposed, opposing each other and further arranged in alinement with respect to the first mentioned pair of binder elements.

3. A check attachment for loom picker sticks comprising a pair of oppositely disposed spring controlled binder elements, means for pivotally connecting the inner ends of said elements to the lower face of a lay at the lever end of the loom, a spacer block adapted to be secured to the lower face of the lay at the battery end of the

loom, a support adapted to be connected to a quill chute at the battery end of the loom and further arranged below the lay, and a pair of spring controlled binder elements one of the elements of said last mentioned pair having its inner end pivotally connected to said block and the other element of said pair having its inner end pivotally connected to said support, said last mentioned pair of binder elements being oppositely disposed, and opposing each other and further arranged in alinement with respect to the first mentioned pair of binder elements, and each of said binder elements having its inner side provided with a wear strip.

4. A check attachment for loom picker sticks comprising a pair of oppositely disposed spring controlled binder elements, means for pivotally connecting the inner ends of said elements to the lower face of a lay at the lever end of the loom, a controlling spring for each of said elements bearing against the outer side thereof, means for connecting said springs to the lay, a pair of oppositely disposed spring controlled binder elements positioned at the battery end of the loom, a spacing block adapted to be secured against the lower face of the lay and having one of the binder elements of the last mentioned pair pivotally connected therewith, a support adapted to be connected with a quill chute and having the other binder element of said last mentioned pair pivotally connected therewith, and controlling springs for said last mentioned pair of binder elements, one of said controlling springs adapted to be secured to a lay and further bearing against the binder elements pivoted to said block, and the other of said springs secured to said support and bearing against the binder element carried by the latter.

In testimony whereof, I affix my signature hereto.

HENRY G. McLEMORE.
